WIRE COVERED ROLL

Application filed May 3, 1930. Serial No. 449,548.

The present invention relates to wire covered rolls and is more particularly directed toward the provision of a wire covered roll for use in paper machines.

5 In paper machines the Fourdrinier wire is carried on a series of small, or table, rolls and is passed about larger rolls. These rolls are subjected not only to the wear of the wire screen but also to the corrosive influence of 10 the chemicals employed in paper making processes. Ordinary iron rolls cannot be employed because the chemicals present cause rapid deterioration. Bronze rolls, which would resist the chemical action and 15 the wear, are of insufficient strength to stand the constant vibration and, hence, are likely to break.

The present invention contemplates a wire covered roll for this purpose, this roll having 20 a wood or metal core and a winding in the form of a compact or closely spaced spiral of wear resistant and non-corrosive wire, preferably of small gauge, so as to present a comparatively smooth surface for 25 the Fourdrinier wire.

The accompanying drawings show several 30 embodiments of the wire covered roll and indicate methods of making the same, it being understood that the drawings are illustrative 35 of the invention rather than limiting the same.

In these drawings:

Figure 1 is a diagrammatic view of a paper 35 making machine indicating the rolls and 40 Fourdrinier wire;

Figure 2 is an enlarged elevational view showing a fragment of a roll;

Figure 3 is a view similar to Figure 2, showing both ends of the roll; and

40 Figures 4 and 5 are transverse and longitudinal sections showing a modification.

Figure 1 illustrates a paper making machine and shows the Fourdrinier wire at 10 and a few of the many table rolls at 11. One 45 of these table rolls is indicated in detail in Figures 2 and 3. It consists of a rigid core 12, turned to the desired diameter and carrying a compact, closely spaced spiral 13 of wire. One way of attaching the end of the 50 wire to an iron core is to apply a solution of

copper sulphate to a spot near the end of the core, thereby depositing copper, as indicated by the stippling 14. The end of the wire may then be coated with soft solder, placed next to the copper coating on the core and a torch applied to heat the wire and core to cause the wire to be soldered to the core. Another way of securing the wire to the core is to apply a small piece or sheet of silver solder to the core. The wire is then applied to the surface of the silver solder and a blow torch or other heating means applied so as to heat the silver and bring about a fusion of the wire, silver and metal roll. This form of attachment affords tremendous strength and high 65 durability.

After the end of the wire is secured to the roll, the rest of the wire is wound onto the roll, making a compact, close spiral, as indicated at 13. During the winding operation the roll is preferably put in a lathe and the wire guided under tension by the carriage of the lathe, the carriage being set to correspond with the diameter of the wire. After the wire is wound on, the other end is 70 soldered to the roll in the manner previously described.

In some cases it is necessary to completely coat the iron core so as to protect it against the action of the mill acids and electrolysis 75 between the wire and core. In such cases the roll 20 may be covered with gold leaf 21, thereby providing a pure gold surface which will be exposed to any moisture. The gold surface is then covered with a layer of asphalt tape, or other insulating material, indicated at 22. An insulating screw 23 is secured in a tapped hole in the body of the roll, and the wire 24 anchored to this screw, after which it is wound on the roll, sinking 80 it into the tape as indicated.

The winding is preferably made of wire of small gauge, say, from twelve to twenty-five gauge, and where round wire is used, it presents a comparatively smooth surface 85 which has no harmful effect on the Fourdrinier wire with which it contacts. In any case, the surface may be made smoother by grinding off the wires, as indicated at 24', in Figure 5, or square wire or flat banding strip 90

may be employed. By employing this process, it is possible to make rolls with non-corrosive wear resistant surface of wire, such as stainless steel, brass, aluminum, bronze, or other material, and at the same time avoid the expense of bronze rolls of less strength. The cost of these wire wound rolls is very much less than the cost of the bronze rolls now in use. These rolls are suitable for table rolls, 5 dryer rolls, or wherever a roll with such a surface is desired.

10 It is obvious that the invention may be embodied in many forms and constructions, and I wish it to be understood that the particular forms shown are but a few of the many forms. Various modifications and changes being possible, I do not otherwise limit myself in any way with respect thereto.

15 The methods herein disclosed form subject 20 matter for a divisional application.

What is claimed is:

25 1. A paper machine comprising a Four-drinier wire passed over a table roll the surface of which is a compact spiral of wear resistant, non-corrosive wire.

30 2. A paper machine comprising a Four-drinier wire supported on rolls having a winding wire of small size to produce a comparatively smooth surface.

35 3. A paper machine comprising a Four-drinier wire supported on rolls having an iron core and a winding of wear resistant, non-corrosive, stainless steel wire of small gauge.

40 4. A roll for paper machines or the like comprising a core of base metal and a compact winding of non-corrosive wear resistant wire of small size to provide a comparatively smooth surface.

45 5. A roll for paper machines or the like comprising an iron core and a compact winding of non-corrosive stainless steel wire of small size to provide a comparatively smooth surface.

50 6. A roll comprising an iron core, a layer of gold leaf on the core, a winding of insulating tape on the gold leaf, and a compact winding of non-corrosive wear resistant wire of small size about the tape.

55 7. A roll comprising an iron core, a layer of gold leaf on the core, a winding of insulating tape on the gold leaf, and a compact winding of non-corrosive wear resistant wire of small size about the tape, the ends of the wire being anchored to insulating posts secured to the core.

HARRISON R. WILLIAMS.
